PROCESS OF ISOLATING HYPOTENSIVE AGENT FROM VERATRUM PLANTS

Gerhard W. Kusserow, Santa Monica, Murle W. Klohs, Glendale, and Philip K. Bates and Kenneth J. Gross, Santa Monica, Calif., assignors to Riker Laboratories, Inc., Los Angeles, Calif., a corporation of Delaware

Application April 6, 1950, Serial No. 154,324

13 Claims. (Cl. 260—236)

This invention relates to hypotensive compositions and to the preparation of hypotensive compositions; more particularly it relates to the extractives and to the extraction of such hypotensive alkaloidal compositions from the drug *Veratrum viride*, also known as American hellebore and green hellebore, and from others of the *Veratrum* genus, such as *Veratrum album*, *Veratrum californicum*, *Veratrum fimbriatum*, and *Veratrum escholtzii*, and from similar plant drugs containing hypotensive alkaloids.

This application is a continuation-in-part of our application Serial No. 92,256, filed May 9, 1949, now abandoned.

While many compositions have been developed and used to lower blood pressure, and the search for more satisfactory remedies for circulatory ailments, including hypertension in particular, has been active, those compositions so far placed at the disposal of the medical profession have been characterized by many disagreeable side reactions, or have been so difficult and hence expensive to prepare that their usefulness in the hands of the physician has been greatly impaired.

We have discovered that hypotensive alkaloidal compositions of outstanding therapeutic value may be obtained from various species of the genus *Veratrum* and kindred drugs, more particularly *Veratrum viride*, *Veratrum escholtzii*, and *Veratrum fimbriatum*, and we have also discovered novel and effective processes for readily segregating such hypotensive compositions.

The compositions derived by our process from *Veratrum viride* and similar species are alkaloidal and have definite activity in lowering blood pressure when administered orally, and have definite physico-chemical characteristics when subjected to the standard tests for purity of organic compounds. Because of their definite therapeutic activity, the physician is enabled to determine readily and speedily the proper dosage for the individual patient. Further, our compositions are nonhabit forming and are especially valuable in that optimum dosages may be administered orally over a considerable period of time without untoward results, building up of tolerances or disagreeable side reactions.

One object of the invention, as indicated in the foregoing, is to provide the medical profession with an improved hypotensive agent derived from *Veratrum* species such as *viride*.

Another object of the invention is to provide a process for the extraction of hypotensive alkaloids from the dried rhizome and roots of *Veratrum viride* and other species.

Another object of the invention is to isolate in a substantially pure form the desirable alkaloidal components from the extractives of the dried rhizome and roots of *Veratrum viride* and other *Veratrum* and similar alkaloidal drug plants.

Another object of the invention is to isolate in the form of an alkaloidal composition those alkaloids derivable from *Veratrum* species and similar alkaloid-bearing plants which are useful and desirable as blood-

2

pressure-lowering agents, or hypotensive agents, while eliminating almost completely all of those accompanying alkaloids which produce therapeutically objectionable side reactions. We have found that many of the better known 5 *Veratrum* alkaloids are not importantly valuable as hypotensive agents and in addition produce objectionable side reactions. They include jervine, rubijervine, isorubijervine, pseudojervine, veratramine, veratrosine, and the like, and these we seek to eliminate.

10 Other objects will become apparent from the following specification, in which *Veratrum viride* is taken as typical of the various *Veratrum* species and similar drug plants containing alkaloidal hypotensive agents.

We have found that a menstruum comprising a solvent 15 for the alkaloidal materials, such as chloroform to which aqueous ammonia (ammonium hydroxide) has been added, extracts the alkaloidal compounds substantially completely from dried ground rhizome and roots of *Veratrum viride*. Chloroform substitutes may be employed 20 in some instances as hereinafter indicated, and, especially, instead of chloroform with aqueous ammonia, anhydrous chloroform or equivalent saturated with ammonia gas may be substituted. The resultant extracted substance, which is a resin-like material, contains not only the desired alkaloids but also impurities and other alkaloidal constituents which produce objectionable side reactions when used therapeutically. Without at present committing ourselves to any particular theory, while it is possible 25 that the ammonia (aqueous ammonium hydroxide) merely increases the solvent effect of the chloroform, it now seems more probable that the desired alkaloidal constituents are naturally present in the drug plant as acidic salts and that these are converted by ammonia to free alkaloid bases which are soluble in chloroform (or similar solvent).

When fresh or undried rhizome and roots are to be treated, owing to their wet condition they are initially extracted with aqueous acetic acid, precipitated with ammonia, and then extracted with ammoniacal chloroform or the like as more fully developed later. This acetic acid extract from the fresh or undried materials is similar 30 in alkaloidal content to the resin-like material obtained by starting with chloroform and ammonia. It is probable that the acetic acid (or equivalent acid herein disclosed) converts the natural alkaloid salts in the drug plant to water-soluble salts which are readily soluble in the water of the acid solution.

An important aspect of this invention is the isolation 35 from the above-described extract of the desirable alkaloid constituents which lower blood pressure without producing therapeutically undesirable side reactions when administered to the patient, the objectionable, more commonly known alkaloids of the various *Veratrum* species and various impurities being substantially or entirely eliminated. Thus, a plurality of desired alkaloids is recovered 45 as the new alkaloidal composition. This composition is made up of amorphous bases not at present positively identified and perhaps one or more of the less known alkaloids of the group commonly derived from the various *Veratrum* species.

60 In the accompanying drawing, the figure is a flow diagram indicative of the general steps of the process of isolation and purification, and also indicative of one acceptable procedure, although variations thereof are disclosed in the following specification.

65 As a first step in one method of purification, the solvent is removed from the resin-like extract as by evaporation under partial vacuum at a slightly elevated temperature, for example, 30° C. to 50° C., which insures against decomposition of the alkaloids. The solvent-free extract 70 is then dissolved in one of the lower alcohols, such as methanol, previously slightly heated.

Instead of employing methanol or other lower alcohol as just indicated, any other appropriate organic, water-miscible alkaloid solvent (which is inert toward or non-reactive with alkaloids) may be employed such as the methyl, ethyl, and butyl ethers of diethylene glycol (known as "Carbitols") and dioxane (also an ether), particularly the latter; or, alternatively dioxane, for example, may be used to displace the ammonia and chloroform by adding the dioxane to the ammonia and chloroform solution (with or without partial evaporation of ammonia and chloroform), and removing the ammonia and chloroform under vacuum, thereby leaving the alkaloids in solution in the dioxane or similar indicated solvent, by reason of the difference in boiling points. Other alcohol substitutes, as hereinafter indicated, also may be used for this purpose. It is to be noted that where the term "inert" alkaloid solvent is used, it is meant to signify one which does not react with the alkaloids or the ammonia present.

The alcohol solution or other indicated organic solvent solution is then poured into a dilute aqueous solution of acid such as acetic acid, hydrochloric acid, or sulphuric acid, or mixtures thereof, with constant stirring to form addition products. After permitting the resultant mixture to stand for a time to effect precipitation of some of the undesired materials, the acidified slurry may be first strained through a coarse meshed fabric material and then through a suitable polishing filter to remove the precipitated inert extracted materials.

By adjusting the clear filtrate to a distinctly alkaline hydrogen ion concentration, preferably within the pH range of 8 to 10, such as pH 9.2, by the addition of an aqueous solution of ammonia (ammonium hydroxide) or alkali metal hydroxide, the desired alkaloids are precipitated along with some undesired impurities. These precipitated alkaloids, after being collected on a filter, washed with water and appropriately dried, comprise a water-insoluble, cream-colored fraction suitable for further purification.

However, this water-insoluble intermediate, cream-colored product is directly usable as a hypotensive composition, inasmuch as it has shown definite value in lowering blood pressure and is distinctly superior to other hypotensive agents now in common use, especially in that it possesses a much reduced tendency to cause undesirable side reactions. In addition to being water-insoluble, it is acid-soluble, alcohol-soluble, dioxane-soluble, and soluble in ammoniacal chloroform and chloroform, but insoluble in ammonium hydroxide. It may be designated as Product A.

Where fresh or undried forms of the plants are to be treated, acetic acid solution (or a solution of an equivalent mineral or organic acid as herein disclosed) adjusted to a pH of about 3.5 is used as the initial extracting agent, in view of the natural water content of the plants. The extract solution thus obtained is rendered ammoniacal, e. g. pH 9.2, to precipitate a desired fraction which is filtered out and then taken up in ammoniacal chloroform (in a manner as previously described), the undissolved residue being discarded. Upon evaporation of the ammoniacal chloroform, a residual product is obtained which is substantially water-insoluble, base-insoluble (e. g. insoluble in ammonium and alkali metal hydroxides and the like), acid-soluble, alcohol-soluble, and dioxane-soluble. Such residue corresponds with the cream-colored intermediate product (Product A) above described as being precipitated by ammonia from an alcohol-acid solution or dioxane-acid solution. This residual product may be combined with such intermediate product, or used or treated separately in the same manner as such intermediate product is used or treated.

The desirable alkaloids are separated from this water-insoluble fraction (Product A) and further purified by additional treatment, such as the following. The fraction, in powdered form, is first dissolved in a dilute aque-

ous solution of an organic or inorganic, nonoxidizing, nonreducing acid such as acetic acid or hydrochloric acid and then treated with a small proportion of an aqueous solution of ammonium sulfate or equivalent reagent adapted to precipitate only the less active alkaloids and leave the active, desired alkaloids in solution. After standing, the less active alkaloids are removed as by filtration, and the precipitate is washed with water. The dissolved alkaloids are precipitated from the combined filtrate and washings by adding an aqueous alkaline solution of ammonium, sodium or potassium hydroxide to yield an appropriate hydrogen ion concentration, preferably between about pH 8 and pH 10, for example, pH 9.2 to pH 9.5. For this purpose, appropriate solutions, such as ten percent or similar solutions, will be added. After most of the water has been removed from the gelatinous precipitate by filtering, the precipitate may be removed from the filter and dried in air below its decomposition temperature, or it may be dried by dissolving with agitation in chloroform in a suitable container, allowing the chloroform and aqueous fluid to separate into distinct layers, drawing off the chloroform layer and treating it with a suitable anhydrous drying agent, and then removing the chloroform by evaporation under vacuum. The residue is further treated by dissolving in a suitable solvent, such as benzol, and filtering to remove additional undesirable material which remains undissolved, after which the filtrate is evaporated to dryness under vacuum. The resultant residue contains the desired alkaloids, free from undesirable contaminants.

This product, which is pale yellow, is highly desirable for its therapeutic value, and may be designated as Product B. It may also be further purified to substantially remove its entire content of less desirable constituents, such as remaining rubijervine and isorubijervine, by taking up in acetone all constituents soluble therein, discarding any undissolved residue and crystalline material which soon forms, and evaporating the separated solution to dryness under vacuum to yield a final acetone-soluble product, which may be designated as Product C.

To convey a better understanding of our invention a typical method of carrying out the process is set forth in the following example, which is not to be considered limitative but is disclosed for illustrative purposes.

EXAMPLE

Extraction of rhizome and root

Approximately 30 lbs. of dried, ground (20 mesh) green hellebore rhizome and root in glass percolators is covered with redistilled technical grade chloroform (about 100 lbs.) containing about one liter of concentrated ammonium hydroxide (about 28% NH₃). After three days the chloroform is drained and another extraction is made with fresh chloroform and ammonium hydroxide. The chloroform extracts are combined and evaporated to dryness under partial vacuum at about 30° C. to 40° C. The yield is about 1.6% to 2.0%.

Preferably, the ammoniacal chloroform extracting solution may be produced by absorbing appropriate proportions of ammonia gas in anhydrous chloroform. Optimum amounts of such absorbed gas appear to be from about 1% to about 2% by weight of the chloroform. Since chloroform is saturated when containing about 2% of ammonia gas, such absorption may amount to saturation in the case of chloroform. Such a solvent has greater extractive value, as does any of the other substitute solvents when containing appropriate amounts of absorbed ammonia gas, as compared with solvents containing aqueous ammonia solution as herein described. In general, 2% of absorbed ammonia appears to be about the upper limit of the optimum range, although, when a solvent is capable of containing somewhat more absorbed ammonia, the content thereof may be increased somewhat, although apparently no additional beneficial

results are obtained. A few per cent, such as 4% or 5%, constitute a practical limit. As a matter of fact, if the percentage is carried too high, there may be a tendency to reduce the proportion of alkaloids extracted from the plants. If a solvent such as methanol is employed, where it is possible to absorb as much as 20% of ammonia gas, such an ammonia gas concentration is to be avoided both because of the tendency to lower extraction capacity, and to avoid saponification which may occur if the plant drug contains any significant proportion of moisture, as when the plant drug is damp or wet.

Purification of crude extract

The resinous chloroform extract is dissolved in about 440 ml. of warm methanol (about 50° C.) (2 ml. per gram of extract). The methanol solution is then poured into about 4.4 liters of 5% aqueous acetic acid, with stirring. This is about one volume of methanol to about 10 volumes of acid solution. After standing for one hour the solution is filtered through ordinary towel cloth, then through a polishing filter using an asbestos filter disk. The clear orange brown filtrate is adjusted to a pH of about 9.2 with concentrated ammonium hydroxide diluted with an equal volume of water to yield about 14% ammonia by weight. A cream-colored precipitate forms and is recovered by filtration. After being thoroughly washed with water the precipitate is dried in a vacuum oven at about 35° C. for about 15 hours with some flow of air through the oven. When dry, the material is a cream-colored powder which will be referred to as the water-insoluble fraction containing the desired alkaloids. The yield is about 0.35% to 0.40% (Product A).

The intermediate cream-colored product (Product A) may be used as such without further purification because it possesses valuable blood-pressure-lowering properties without significantly objectionable factors. Its physico-chemical characteristics are as follows:

Description.—An off-white, cream-colored powder which is very sternutative;

Solubility.—Easily soluble in many organic solvents such as methyl alcohol, ethyl alcohol, chloroform, acetone, propylene glycol, ethylene glycol monomethyl ether (methyl "Cellosolve"); partially soluble in benzene and ether (ethyl ether); substantially insoluble in water;

Optical rotation range.— $[\alpha]_D^{27} = -73^\circ$ to -110° at a concentration of 0.5 gram per 100 ml. in 95% ethyl alcohol;

Ultraviolet absorption.—Strong absorption peak at 250 millimicrons at which the calculated specific extinction coefficient is approximately 19,000 to 23,000 based on a concentration of 0.000016 gram per ml. of 95% ethyl alcohol;

Nitrogen content.—Approximately 2.9%;

Sulfuric acid color test.—When dissolved in concentrated sulfuric acid on a spot plate, gives a yellow color which changes to brown on standing.

As previously indicated, this product, in addition to the stated solubilities above, is also soluble in dioxane, in acetic acid and other described acids, and in ammoniacal chloroform, but is insoluble in ammonium hydroxide solutions and similar aqueous basic solutions, at least at a pH above about 8.

Separation of the desirable alkaloids from the water-insoluble fraction

The water-insoluble fraction obtained above (approximately 52 gms.) is dissolved with stirring in about 1000 ml. of 5% aqueous acetic acid (about 20 ml. per gram of the precipitate constituting the above Product A). To this solution is added about 100 to 105 gms. of reagent grade ammonium sulfate dissolved in 250 ml. of water (about 30% solution). After standing for one hour the resultant precipitate is removed by filtration and washed with water on the filter. The filtrate and washings are

combined and adjusted to a pH of 9.4 to 9.5 with concentrated ammonium hydroxide and the precipitate formed is recovered by filtration. After most of the water has been removed from the gelatinous precipitate on the filter funnel, the precipitate is dissolved in an excess of chloroform by shaking in a separatory funnel. The chloroform layer is removed and dried with anhydrous sodium sulfate. The dried chloroform layer is evaporated to dryness under vacuum and the residue dissolved as much as possible by shaking with 250 ml. of benzene (benzol). The benzene solution is filtered and the filtrate evaporated to dryness under vacuum, yielding a pale yellow product that contains the alkaloids most desirable for blood pressure lowering. The yield is about 0.06% to 0.10% (Product B).

This pale yellow product is preferably further treated to remove the remaining less desirable rubijervine and iso-rubijervine constituents by shaking with about 250 ml. of acetone to dissolve the constituents soluble therein, filtering and recovering the solution, and evaporating to dryness under vacuum to yield a final pale product which may be designated as straw-colored. The yield is about .04% to .07% (Product C).

Products B and C, as apparent from the foregoing descriptive matter, are water-insoluble, soluble in solutions of nonoxidizing and nonreducing acids of the character indicated, soluble in the lower alcohols, soluble in dioxane, and soluble in chloroform and ammoniacal chloroform, but insoluble in aqueous alkaline solutions such as ammonium and alkali metal hydroxide solutions, at least above a pH of about 8. They are also soluble in benzol, and acetone, and moreover are soluble in indicated aqueous acid solutions containing ammonium sulfate, whereas some of the objectionable alkaloids which are soluble in the acid solutions themselves are precipitated as sulfates in the presence of ammonium sulfate. Similarly, while the desirable alkaloids are precipitated from such an acid solution, containing ammonium sulfate, upon addition of ammonium hydroxide to render the solution alkaline, certain undesirable alkaloids remain in the solution and are discarded upon filtration.

The processes herein described are desirably carried on in glass or similar apparatus, or in stainless steel apparatus, to insure against possible contamination by materials of which the apparatus might otherwise be constructed.

Except as otherwise indicated as important and limiting, operations are ordinarily conducted under room temperatures and pressures, and proportions may be varied considerably as will be understood by the chemist. In connection with drying temperatures, where reference has been made to drying at about 30° C. to 40° C., it will be appreciated that both higher and lower temperatures may be employed, according to the particular drying method used. If higher temperatures are employed, they should not exceed about 95° C. because decomposition starts at about 100° C. and becomes serious at about 105° C. Similarly, considerably lower temperatures may be employed where low temperature drying processes are acceptable, and possibly drying may then occur at temperatures as low as -70° C. In connection with employment of warm solvents, the upper temperatures ordinarily will be readily controlled by reason of the comparatively low boiling point of the solvent. Otherwise, it is obvious that the temperatures will be regulated to avoid decomposition.

Obviously, many modifications of the process as above described, may be made without departing from the spirit of the generic invention presented. Thus, acetone, benzene, ether, or other volatile organic alkaloid solvent capable of absorbing ammonia and inert or nonreactive toward the alkaloids, such as carbon tetrachloride and the like, may be substituted for chloroform in the initial extraction of the ground *Veratrum viride* or other *Veratrum* species. Other lower aliphatic alcohols up to about eight carbons per molecule, such as ethyl, propyl, iso-

propyl, amyl, and hexyl alcohols and mixtures thereof, or other water-miscible solvents or mixtures thereof, may be substituted for methanol in the process. Such water-miscible solvents are particularly the water-miscible ethers, such as m-dioxane and p-dioxane, and the alkyl ethers of diethylene glycol (commonly known as the "Carbitols") such as the monomethyl, monobutyl, monoethyl, and diethyl diethylene glycols. Other examples of such water-miscible solvents are glycerine, propylene glycol, and the methyl, ethyl, butyl, and benzyl glycol ethers known as the "Cellosolves."

Instead of the acetic acid particularly mentioned, other dilute acids may be used, for example, citric acid, tartaric acid, sulfuric acid, hydrochloric acids and mixtures thereof. In practice these acids are commonly used in relatively dilute water solutions, such as the 5% acetic acid solution previously mentioned. In each instance where acid generically is mentioned, it is understood that, for this purpose, the acid shall be a nonoxidizing, nonreducing, dilute, aqueous acid solution, the acid being a freely water-soluble organic or inorganic acid capable of combining with the alkaloidal constituents present to form the water-soluble acid addition salts of the desirable alkaloids as well understood in this art. By this definition it is intended to exclude such acids as nitric acid, sulfuric acid, chromic acid, perchloric acid, and the like, at least under conditions in which oxidization or reduction might take place. This, of course, will be obvious to the organic chemist.

Similarly, where the use of ammonium hydroxide has been indicated, the alkali metal hydroxides may be employed to replace ammonium hydroxide except where the solvent employed must be volatile as in the case of the initial chloroform extraction step in which ammonium hydroxide is used. Otherwise mixtures of these alkaline materials, including ammonium, sodium, and potassium hydroxides and mixtures thereof, or other appropriate alkaline solutions, may be used interchangeably. Commonly these alkaline materials are used in concentrations to yield a pH value of about 9.2, and sometimes a pH value of 9.4 or 9.5. The usual operative range is between about pH 8 and pH 10, or in other words, appreciably higher than pH 7. Ordinarily a pH above 10 will not be employed because a higher pH tends to saponification or kindred reaction with the desired alkaloidal materials undergoing treatment.

In connection with the previously mentioned use of anhydrous drying agents, in addition to employment of anhydrous sodium sulfate, other anhydrous drying agents, such as calcium sulfate, calcium chloride, and copper sulfate, may be employed, as may many of the well-known means for removing fluids from precipitates or separating immiscible liquids, such as centrifuging, which yield satisfactory results when employed in the process instead of filtering.

Respecting the employment of ammonium sulfate to precipitate undesired alkaloids, the proportion used is between about one-quarter gram and about four grams per gram of dissolved precipitate in the solution being treated. The optimum is about two grams of ammonium sulfate per gram of dissolved precipitate. The proportion of about four grams is approximately the upper practical limit because, as the proportion of four grams is exceeded, such greater proportion of ammonium sulfate begins to throw out the desired alkaloids. It will be noted that the ammonium sulfate solution indicated in the above example is a fairly strong solution containing about 30% of ammonium sulfate. Such strong solution is desirable inasmuch as it reduces the volume of total solution to be handled. Instead of ammonium sulfate it is sometimes feasible to use such sulfates as the alkali metal sulfates and the alkaline earth metal sulfates. Since it is the small concentration of the sulfate radical which is important, it will sometimes be possible, though apparently not so desirable, to use a minor proportion of

sulfuric acid, for example around 1% to 1.5% H_2SO_4 based on the total solution.

In addition to the pale yellow product obtained as above described, which contains the most desirable alkaloids, other alkaloids may be obtained from the ammoniated filtrates indicated in the "purification" and "separation" paragraphs of the above example, appropriate solvents and precipitants, such as those herein disclosed, being employed to separate the respective alkaloids by steps similar to those steps described above.

Having particular reference to the pale yellow product (Product B) of the example, this blood-pressure-lowering alkaloidal fraction possesses the following physico-chemical characteristics:

15 Solubility.—Easily soluble in most organic solvents such as methyl alcohol, ethyl alcohol, chloroform, benzene (benzol), ether, acetone, ethylene glycol, monomethyl ether (methyl "Cellosolve"), ethyl acetate, methyl ethyl ketone and propylene glycol; substantially insoluble in water, the lower boiling petroleum fractions such as petroleum ether, and cyclic paraffins;

20 Optical rotation range.— $[\alpha]_D^{26} = -15^\circ$ to -35° at a concentration of 0.5 gram per 100 ml. in 95% ethyl alcohol;

25 Ultraviolet adsorption.—Absorption peak at 250 to 254 millimicrons at which the calculated specific extinction coefficient is approximately 4,000 to 6,000 based on a concentration of 0.00008 gram per ml. of 95% ethyl alcohol; there is also a definite leveling off in the absorption spectrum curve at 280 to 300 millimicrons and the calculated specific extinction coefficient using 290 millimicrons as an average is approximately 820 to 1640 based on a concentration of 0.0004 gram per ml. of 95% ethyl alcohol;

30 Nitrogen content.—Approximately 2.9%;

35 Sulfuric acid color test.—When dissolved in concentrated sulfuric acid on a spot plate, gives a bright orange brown color which changes to a light brown upon standing.

40 Having reference to the straw-colored final product (Product C) of the example produced by a final extraction with acetone, the characteristics of this composition are in general the same as those above given for the pale yellow product, except as differently indicated below. These characteristics are as follows:

45 Color, appearance, taste.—Straw-colored powder, strongly sternutatory, and having a bitter acrid taste;

50 Optical rotation.— $[\alpha]_D^{25} = -25^\circ \pm 7^\circ$ (Concentration = 0.5% in ethanol);

55 Spectrophotometric characteristics.—

$\log E_{250} \text{ mu} = 3.75 \pm 0.20$

$\log E_{290} \text{ mu} = 3.02 \pm 0.20$

(Unit of concentration 1 gm./cc. in ethanol);

55 Equivalent weight.—550 $\pm$ 50;

57 Nitrogen based on equivalent weight.—2.33% to 2.80%;

60 Percent volatile matter.—Not greater than 5% when determined at 1 mm. Hg at 70° C.;

62 Sintering point.—100° C.;

64 Melting point.—135° C.;

66 Solubility.—**Distilled water.**—Insoluble. **Acetone.**—99%+ soluble at a concentration of 40 mg. per cc. of solvent at 25° C. **Benzene.**—80%+ soluble at a concentration of 80 mg. per cc. of solvent at 25° C.

70 Having reference to the previously indicated acetic acid extraction of fresh or undried *Veratrum viride* and similar plants containing hypotensive agents, the extraction is made with dilute acetic acid (or dilute equivalent acid as heretofore disclosed). Upon completion of the acid extraction, the solution is removed and made ammoniacal (e. g. pH 9.2) with ammonium hydroxide, thereby producing a precipitate which is recovered by filtration. The filtrate may be treated for recovery of a product as hereinafter disclosed. The precipitate is taken

up in ammoniacal chloroform produced as heretofore described, or equivalent solvent, the undissolved residue being discarded and the filtrate being evaporated to dryness under vacuum to yield a solid product. (This procedure may also be used on the dried plant drugs, but is not economically desirable for that purpose.) This product corresponds with the cream-colored intermediate product above described (Product A) which is precipitated from an acetic acid-alcohol solution or from an acetic acid-dioxane solution by rendering alkaline with ammonium hydroxide, and then recovered as a precipitate. This acid-extracted residual product obtained by the evaporation of the ammoniacal chloroform may be used as such, or mixed with the described intermediate cream-colored product. Also, it may be further purified with, or in the same manner as, such intermediate product to yield final products corresponding with those previously described (Products B and C). Like the cream-colored intermediate product, this residual product recovered by the evaporation of the ammonia-chloroform solvent is substantially alkali-insoluble, water-insoluble, soluble in the described acids, soluble in chloroform, and soluble in the described alcohols or ethers such as methanol or dioxane.

EXAMPLE

As an example of a specific procedure of acid extraction of a freshly harvested (undried) plant drug, the following is given:

Extraction of plant

Approximately 8 pounds of ground, undried, green hellebore containing about 85% moisture is placed in a glass percolator and covered with 10% aqueous acetic acid (about 8 pounds). After standing for 16 hours the extract is drained.

NOTE.—Taking into consideration the moisture content of the drug in this example the acetic acid in the total water present is about 5.5% and the ratio of total menstruum to dry material (solids) is in the order of 12 to 1 by weight. These figures are not critical. The acid strength can vary from 5% to 6% and the ratio of menstruum to solids from, say, 10 to 1 up to 14 to 1. However, the concentration and quantity of menstruum added should preferably be adjusted within these limits based on the approximate moisture content of the drug.

Purification of crude extract

The aqueous acid extract is adjusted to a pH of 9.5 with concentrated aqueous ammonium hydroxide (28% NH₃). The precipitate formed is recovered by filtration, and after being thoroughly washed with water is dried in a vacuum oven at about 35° C. with some flow of air through the oven. The yield is 0.3% to 0.5% (dry basis for starting drug).

The dried material is then treated with about 300 ml. of chloroform to which 10 ml. of 28% aqueous ammonia has been added (or preferably with a chloroform solution of gaseous NH₃) to dissolve as much as possible of the material. The chloroform-insoluble residue (which is chiefly inert impurities) is removed by filtration and the chloroform extract is evaporated to dryness under vacuum. The material, when dry, is a cream-colored powder corresponding with that heretofore referred to (Product A) as the water-insoluble fraction containing the desired alkaloids and also designated as the intermediate product. The yield is 0.15% to 0.25% (dry basis).

As previously indicated, other useful alkaloids may be obtained from the ammonia filtrates obtained upon precipitation with ammonium hydroxide from acetic acid-alcohol solutions (or other acid-alcohol solutions of disclosed acids and alcohols), or from acetic acid-dioxane solutions (or other acid and water-miscible ether or similar solutions disclosed). Similar desirable alkaloids are similarly obtainable from the above described ammonia

filtrate obtained upon neutralization with ammonium hydroxide of the acetic acid solution produced in extracting fresh or undried starting materials. Both types of ammonia filtrates mentioned are to be treated in the same manner, and may be combined for such treatment. The treatment consists in extracting desired constituents from the ammonia filtrates with chloroform. Chloroform is admixed in any preferred manner with the aqueous ammoniacal filtrate, as by agitation therewith in sufficient quantity to extract from the aqueous ammonia filtrate all of the chloroform-soluble constituents. The chloroform solution is then allowed to stratify and separate from the aqueous layer.

The chloroform solution is then evaporated to dryness under vacuum to yield a chloroform-soluble residue which constitutes a therapeutically useful intermediate product. This may be designated as Product D.

A further purified product may be obtained from the chloroform-soluble fraction by ether extraction, any undissolved residue being discarded and the ether solution evaporated to dryness under vacuum to yield the desired further purified product. This may be designated as Product E.

More specifically, the clear, aqueous ammoniacal filtrate used as the starting material for this phase of the invention, which commonly has a pH of about 9.2, is extracted in a continuous extractor with chloroform for about sixteen hours or more until all of the chloroform-soluble constituents have been taken up in the chloroform. This chloroform extract is then evaporated to dryness under vacuum. It is partially water-soluble. It contains desirable hypotensively active alkaloids. The yield is about 0.09% to 0.14%. The physicochemical characteristics of this chloroform-soluble extract (Product D) are as follows:

Solubility.—Readily soluble in methyl alcohol, ethyl alcohol, chloroform, propylene glycol and methyl "Cello-solve"; partially soluble in dioxane, acetone, ether, benzol and water;

Optical rotation range.—[α]_D²⁶ = -10° to -25° at a concentration of 0.5 gram per 100 ml. 95% ethyl alcohol;

Ultraviolet absorption.—Has an absorption peak at 250 to 254 millimicrons at which the calculated specific extinction coefficient is approximately 5,000 to 7,000 based on a concentration of .00008 gram per ml. of 95% ethyl alcohol;

Nitrogen content.—Approximately 2.4%;

Sulfuric acid color test.—When dissolved in concentrated sulfuric acid on a spot plate gives a reddish-brown color which changes to brown upon standing.

When it is desired to eliminate some of the less desirable agents from the last described chloroform-soluble, partially water-soluble extract, the residual product obtained by the evaporation of the chloroform to dryness is taken up in anhydrous ether and the ether extract evaporated to dryness under vacuum.

More particularly, this residual chloroform-soluble product is extracted five times with successive portions of anhydrous ether (ethyl ether), using 200 ml. of ether per 10 grams of material in each portion. The ether extract is then evaporated to dryness under vacuum. The residue is a light tan-colored resinous material containing desired hypotensively active alkaloids free from some of the less desirable alkaloids contained in the chloroform-soluble starting residue. The yield is about 0.04% to 0.06%.

The light tan-colored product just described (Product E) is a desirable therapeutic, blood-pressure-lowering alkaloidal fraction possessing the following physico-chemical characteristics:

Solubility.—Readily soluble in chloroform, dioxane, ether, benzene, ethyl alcohol, methyl alcohol, propylene glycol, acetone and methyl "Cello-solve"; partially soluble in water;

Optical rotation range.—[α]_D²⁶ = -6° to -20° at a

concentration of 0.5 gram per 100 ml. 95% ethyl alcohol;

Ultraviolet absorption.—Has an absorption peak at approximately 250 millimicrons at which the calculated specific extinction coefficient is 4,500 to 7,500 based on a concentration of 0.00008 gram per ml. of 95% ethyl alcohol;

Nitrogen content.—Approximately 2.3%;

Sulfuric acid color test.—When dissolved in concentrated sulfuric acid on a spot plate gives a reddish-brown color which changes to brown upon standing.

If desired, anhydrous benzol may be substituted for the anhydrous ether for extracting the described chloroform-soluble, partially water-soluble fraction, and the product thereby obtained has physico-chemical characteristics which are substantially the same as those of the anhydrous ether extract.

The above described processes may be used also for the recovery and isolation of kindred alkaloids from similar alkaloid-bearing plants.

Having particular reference to Product C of this invention, the constituents are amorphous or noncrystalline forms of alkaloids which are almost wholly water-insoluble. Apparently they are principally unidentified amorphous bases possibly containing one or more of the known amorphous alkaloids from *Veratrum* species. However, this composition is substantially free from cevadine (which is water-soluble) and veratridine, these two together being sometimes referred to as veratrine. This product is also substantially free from the commonly known *Veratrum* alkaloids particularly jervine, rubijervine, isorubijervine, pseudojervine, veratramine, veratrosine, and the like. Thus, our process results in eliminating from the *Veratrum* alkaloids those alkaloids which are commonly crystalline and at the same time produce therapeutically undesirable side reactions. In other words, we have been able to isolate an alkaloidal composition which contains only the desirable hypotensively active alkaloids, only traces of the usual crystalline, objectionable alkaloids being found.

In Product B, some of the crystalline, better known *Veratrum* alkaloids are found, more particularly rubijervine and isorubijervine, but the proportion of these is small enough and the objectionable characteristics are so minor, at least in the presence of the other constituents, that Product B is highly desirable as a hypotensive agent except possibly with highly sensitive patients.

While Product A contains larger proportions of the commonly known crystalline type of alkaloids, nevertheless, the high content of amorphous constituents renders the composition much more desirable than *Veratrum* products heretofore available, in that objectionable side reactions are minor.

Products D and E are partially water-soluble, amorphous alkaloid compositions, with scarcely a trace of crystalline alkaloids, and have been found to have very good hypotensive characteristics, although apparently not the equivalent of those of Product C.

Where the term "crystalline" or "crystalline-type" is applied to various alkaloids, it signifies those which are commonly known as such and are recoverable in crystalline form, and the term "amorphous" applies to those alkaloids which are now characteristically separable in amorphous form.

Inasmuch as many variations of the generic invention herein disclosed will become apparent to those skilled in this art, it is intended to protect all modifications falling within the scope of the patent claims.

We claim as our invention:

1. A process for isolating hypotensive alkaloids substantially free from those having objectionable side reactions, said process including the steps of: obtaining a solution of alkaloids from plants of the *Veratrum* family in an ammoniacal organic solvent for said alkaloids; dissolving in an aqueous solution of a non-oxidizing, non-

reducing acid those alkaloids soluble therein which are found in said ammoniacal organic solvent; adding ammonium sulfate to such acid solution to precipitate alkaloids having therapeutically objectionable side reactions; rejecting the insolubles formed in such acid solution; precipitating alkaloid fractions from the resultant acid solution, following removal of said insolubles, by alkalizing with an agent from the class consisting of ammonia and alkali metal hydroxides; dissolving the last-mentioned precipitate in chloroform; evaporating to dryness; taking up from the residue in benzene those fractions soluble therein; and recovering the benzene soluble fractions as a hypotensive composition of alkaloids.

2. A process for isolating a mixture of hypotensive alkaloids from *Veratrum* plants containing the same, which process comprises the steps of: obtaining a solution of the *Veratrum* alkaloids in an aqueous solution of a non-oxidizing, non-reducing acid; adding to said solution sulfate ions to precipitate sulfates of undesired alkaloids; rejecting the insolubles formed thereby; rendering the resulting solution alkaline to produce a precipitate of alkaloids; dissolving the last-mentioned precipitate in chloroform; evaporating to dryness; taking up from the residue in benzene, those alkaloids soluble therein; and recovering the benzene-soluble alkaloids as a hypotensive composition.

3. A process as defined in claim 2, in which the solution of *Veratrum* alkaloids in said aqueous solution of said acid is obtained by a series of steps including: extracting *Veratrum* plants with an organic alkaloid solvent made alkaline with ammonia; replacing such solvent and ammonia with a water-miscible organic alkaloid solvent; mixing the resulting solution with an aqueous solution of a non-oxidizing, non-reducing acid; and rejecting materials insoluble in said last-mentioned aqueous solution.

4. A process as defined in claim 3, in which the first-mentioned organic alkaloid solvent is chloroform containing ammonia gas dissolved therein.

5. A process as defined in claim 3, in which the first-mentioned organic alkaloid solvent is chloroform containing ammonia gas dissolved therein; and said water-miscible organic alkaloid solvent is dioxane.

6. A process as defined in claim 2, in which the solution of *Veratrum* alkaloids in said aqueous solution of said acid is obtained by a series of steps including: extracting *Veratrum* plants with chloroform containing ammonia gas dissolved therein; replacing said chloroform and ammonia with dioxane; mixing the resulting solution with an aqueous solution of acetic acid; and rejecting materials insoluble in said aqueous solution of acetic acid.

7. The process as defined in claim 6, in which the alkaloids soluble in said aqueous solution of acetic acid are precipitated by rendering said aqueous solution alkaline; and the precipitated alkaloids are separated and again dissolved in an aqueous solution of acetic acid.

8. A process as defined in claim 2, in which the solution of the *Veratrum* alkaloids in said aqueous solution of said acid is obtained by a series of steps including: extracting *Veratrum* plants with an aqueous solution of acetic acid; rendering the extract alkaline to precipitate *Veratrum* alkaloids; recovering in solution in chloroform the chloroform-soluble alkaloids, the insolubles being rejected; evaporating the resulting solution of alkaloids to dryness; and dissolving the residue in an aqueous solution of a non-oxidizing, non-reducing acid.

9. A process as defined in claim 2, in which said non-oxidizing, non-reducing acid is acetic acid.

10. A process as defined in claim 2, in which the sulfate ions are added in the form of ammonium sulfate.

11. A process as defined in claim 2, in which the last-mentioned composition is dissolved in acetone and any insoluble material and crystalline precipitate forming therein is discarded; and the soluble material recovered as a further purified hypotensive composition.

12. A process for isolating a mixture of hypotensive

alkaloids from Veratrum plants containing the same, which process comprises the steps of: initially extracting the plants with chloroform containing ammonia gas absorbed therein to obtain a solution of alkaloids; replacing the chloroform and ammonia in said solution with dioxane; thereafter replacing said dioxane with an aqueous solution of acetic acid while rejecting materials insoluble in said acid solution; adding ammonium sulfate to said acid solution to precipitate sulfates of undesired alkaloids; rejecting the insolubles formed thereby; rendering the resulting solution alkaline with ammonia to produce a precipitate of alkaloids; dissolving the last-mentioned precipitate in chloroform; evaporating the resulting chloroform solution of alkaloids to dryness; taking up the residue in benzene; discarding insoluble material; evaporating the remaining benzene solution of alkaloids to dryness; taking up the resulting residue in acetone; discarding any insoluble material and any crystalline precipitate which forms in said acetone; and recovering the remaining acetone-soluble alkaloids as a hypotensive composition.

13. A process for isolating a mixture of hypotensive alkaloids from Veratrum plants containing the same, which process comprises the steps of: initially extracting the plants with chloroform containing ammonia gas absorbed therein to obtain a solution of alkaloids; replacing the chloroform and ammonia in said solution with dioxane; thereafter replacing said dioxane with an aqueous solution of acetic acid while rejecting materials insoluble in said acid solution; rendering said acid solution alkaline with ammonia; filtering out the resultant precipitate; dissolving such precipitate in acetic acid; adding ammonium sulfate to said acid solution to precipitate sulfates of undesired alkaloids; rejecting the insolubles formed thereby; rendering the resulting solution alkaline with ammonia to produce a precipitate of alkaloids; dissolving the last-

5 mentioned precipitate in chloroform; evaporating the resulting chloroform solution of alkaloids to dryness; taking up the residue in benzene; discarding insoluble material; evaporating the remaining benzene solution of alkaloids to dryness; taking up the resulting residue in acetone; discarding any insoluble material and any crystalline precipitate which forms in said acetone; and recovering the remaining acetone-soluble alkaloids as a hypotensive composition.
